No. 663,304.

Patented Dec. 4, 1900

F. THEILENGERDES.
MAGNETIC SEPARATOR.

(Application filed June 8, 1900.)

(No Model.)

Inventor
Frederick Theilengordes
by Hall and Greene, Attorney.

UNITED STATES PATENT OFFICE.

FREDERICK THEILENGERDES, OF MEMPHIS, TENNESSEE, ASSIGNOR OF ONE-HALF TO WALTER GOODMAN, OF SAME PLACE.

MAGNETIC SEPARATOR.

SPECIFICATION forming part of Letters Patent No. 663,304, dated December 4, 1900.

Application filed June 8, 1900. Serial No. 19,531. (No model.)

To all whom it may concern:

Be it known that I, FREDERICK THEILENGERDES, a citizen of the United States, residing at Memphis, county of Shelby, State of Tennessee, have invented a new and useful 5 Magnetic Separator, of which the following is a specification.

The object of this invention is to provide means whereby fragments of iron or other 10 magnetic substance may be separated from granular or pulverized non-magnetic material. It often happens that in treating grain or seed of any kind the operating devices are seriously injured by nails, bits of wire, and 15 the like which are by chance present in the material operated upon. In certain cases, particularly in removing lint from cotton-seed, even more serious results follow, for the sparks caused by the fragments of iron set 20 fire to the very inflammable lint, and if the fire be not quickly controlled it is very likely to extend from the lint within the machine to lint without it, and thus cause loss far beyond mere injury to the machine. All the evils 25 suggested are avoided by passing the material to be operated upon in a thin stratum over an inclined plate or feed-board having in or near its surface and extending across the same a strong electromagnet which will 30 arrest and securely hold all magnetic fragments or bodies in the material passing down the incline.

For illustration I have shown the devices as combined with the common swinging feed-board of a cotton-gin or delinter, and in the 35 accompanying drawings—

Figure 1 is a transverse vertical section of such feed-board provided with my devices. Fig. 2 is a view in the direction of the arrow 2 40 of Fig. 1. Fig. 3 shows the apparatus as seen in looking toward the free edge of the feed-board, a portion on the left being broken away to show a section on the line 3 3, Fig. 2.

In the views, A represents a feed-board 45 adapted to be located and mounted as in ordinary machines of this kind—that is, extending from side to side of the machine—and hinged, as at A', so that its lower edge may be swung inward or outward at will, varying 50 the position of its surface A², down which passes the material to be operated upon.

Upon the lower opposite side of the feed-board is a flat magnetic coil B, extending nearly from end to end of the board, provided with non-conducting end plates B', and having a 55 thin soft-iron core C, whose projecting ends C' C' are bent upward at right angles and extended nearly through the board to meet parallel bars C² C², fixed in magnetic contact with the ends C' C' by screws C³ and forming the 60 positive and negative pole-pieces, respectively, of the magnet and preferably projecting slightly beyond the general surface of the board. The end plates B' are laterally supported by lugs B² from the ends of the core, 65 and the bars C² may advantageously be secured to the central portion of the board by screws D. As the board is conveniently made in three pieces, the parts are all rigidly bound together by bolts E, preferably of non-magnetic 70 metal. The coil is in circuit with any suitable source F of electrical energy, and the circuit is provided with any suitable make and break devices F'.

If the circuit be closed, the magnet will be 75 energized, and the magnetic force will be the same from end to end of the bars or pole-pieces, and either (or both, if the body be long enough to act like an armature) will attract and hold magnetic bodies or particles that 80 may be in the passing materials. By having two distinct bars or pole-pieces which, though one is positive and one negative, will each hold magnetic bodies any such bodies which by any chance fail to come in contact with the 85 first will probably be caught by the second, and by having each raised or projecting above the board's surface the chance of failure to arrest any particle is still further diminished, and in practical use of this device for a long 90 period not a single failure is known to have occurred.

The exact construction set forth need not be followed. For example, the bars or pole-pieces may be integral with the core, and the 95 one-piece core and pole-pieces may be formed by slotting from end to end a tube approximately as long as the width of the sheet of material to be treated, or the ends of the core may simply be bent once, so that the edge 100 faces alone will be presented to the passing cotton-seed or other material.

What I claim is—

The combination with the inclined hinged feed-board, of the flat electromagnet-core beneath and extending nearly from end to end 5 of the same and having its broad ends turned upward into slits in the board, approximately parallel bars of magnetizable material sunk in the upper surface of the board and resting upon said ends, non-conducting plates resting against the upturned ends and oppositely-

extending lugs, and a coil wound about the core between said plates, substantially as set forth.

In testimony whereof I affix my signature in the presence of two witnesses.

FREDERICK THEILENGERDES.

Witnesses:
